ULTRA SHORT WAVE OSCILLATION
GENERATOR

Dietrich Prinz and Hans Otto Roosenstein, Berlin, Germany, assignors to Telefunken Gesellschaft für Drahtlose Telegraphie m. b. H., Berlin, Germany, a corporation of Germany

Application June 14, 1933, Serial No. 675,680
In Germany June 28, 1932

6 Claims. (Cl. 250—36)

The present invention relates to thermionic oscillation generators for the production of extremely high frequencies, and particularly to such generators of the screen grid type.

In the majority of circuit arrangements for the production of short waves, the use of screen grid tubes is attended with difficulties due to the fact that the screen grid is in radio frequency connection with the cathode and tends to increase the grid-filament and the plate-filament capacitance. As a consequence there is a shift in the frequency to which the grid and the plate circuits are naturally resonant. Circuit arrangements may be provided, however, wherein the length of the generated wave is merely a function of the resultant grid plate capacitance, i. e., of the composite capacity due to the series arrangement of the grid filament and the plate filament capacitances, and the grid plate capacitance arranged in parallel thereto. This latter capacitance in circuit arrangements of this kind should as far as possible be minimized. The capacities of the part of the oscillation circuit located externally of the tube between grid and filament, and between filament and plate, are to be understood as being included in the grid-filament capacitance and the filament-plate capacitance.

A circuit scheme in which the wave length depends solely upon the resultant grid-plate capacitance as above defined, will be obtained, for instance, by associating the grid with the plate by means of the coil contained in the oscillation circuit, the feed-back being obtained by the internal tube capacitances. The sole figure of the drawing shows a circuit scheme of this sort. Referring to this figure, condenser 1 serves here merely as a block condenser in that it is used for the purpose of precluding the plate D. C. voltage from becoming active at the grid. 2 and 3 denote choke coils for the supply of grid and plate D. C. voltage.

Now, when screen grid tubes are used in a circuit scheme such as that which has just now been discussed, the resultant grid-plate capacity need not be essentially higher than would be the case if there were no screen grid. In fact the grid and plate might have the same dimensions as would be preferred in a tube of the triode type. It is possible, therefore, to tune such a circuit to as short a wave length when employing a screen grid tube as would be possible using a triode tube. The gain reciprocal, however, may be substantially lower, although the feed-back factor is not less than in a standard triode tube of the same dimensions. An examination of the

feed-back equation shows that, as a consequence, the production of oscillations would still be feasible in the presence of frequencies for which the low impedance of the oscillation circuit would entirely preclude all chances of exciting oscillations in normal tubes.

In other words, the invention consists, in the first place, in the use of screen grid tubes in extremely high frequency oscillation generator circuit arrangements of the sort above described; and secondly, in choosing proportions and dimensions whereby the direct grid and plate capacitance of the tube is reduced to a minimum value. Such dimensioning is determined from the consideration that, in a normal tube, the optimum grid-plate alternating voltage for maximum efficiency presents a phase difference of 180 degrees so that between the grid and the plate there exists a region or plane of constant potential. Mounting in this surface a metallic wire network which is connected with the cathode, it will be seen that this will evidently not cause any alteration at all in the distribution of the radio frequency potentials, nor in the grid-plate capacitance. Now, according to this invention, the screen grid is placed in the region which is at constant potential.

It will be readily understood that in a tube of the said kind the capacity C_{sa} between the screen grid and the plate is to the capacity C_{gs} between the control grid and the screen grid as the optimum control grid alternating voltage E_g is to the optimum plate alternating voltage E_a , thus:

$$\frac{C_{sa}}{C_{gs}} = \frac{E_g}{E_a}$$

What follows therefrom for a cylindrical arrangement is

$$\frac{\ln \frac{r_a}{r_s}}{\ln \frac{r_s}{r_g}} = \frac{E_g}{E_a}$$

where r_a , r_s , and r_g are the radii of the plate, the screen grid, and the grid and $\ln$ designates the natural logarithm. In the case of a plano-parallel form of construction there holds good

$$\frac{E_g}{E_o} = \frac{d_{sa}}{d_{gs}}$$

where d_{sa} the distance intervening between the screen grid and the plate, and d_{gs} is the distance between the control grid and screen grid.

We claim:

1. An oscillation generator circuit for the pro-

duction of extremely high frequencies comprising an electron discharge device having an anode, cathode, control electrode, and screen electrode, an oscillatory circuit between said anode and control electrode, said screen electrode being located at a point of substantially constant alternating potential between said anode and cathode.

2. An oscillation generator circuit for the production of extremely high frequencies comprising an electron discharge device having an anode, cathode, control electrode, and screen electrode, and an inductance between said anode and control electrode, the oscillatory circuit of said generator comprising said inductance and the internal capacity of said device, means for maintaining said screen at a positive potential relative to said cathode, said screen being positioned in said device at a location which, as regards alternating voltage, is substantially at cathode potential.

3. An oscillation generator circuit for the production of extremely high frequencies comprising an electron discharge device having an anode, cathode, control electrode, and screen electrode, an oscillatory circuit between said anode and control electrode, the dimensions of said electrodes being such that the ratio between the screen to anode capacitance and the screen to control electrode capacitance corresponds substantially to the ratio between the optimum alternating voltages of the control electrode and anode.

4. An oscillation generator circuit for the production of extremely high frequencies comprising

an electron discharge device having an anode, cathode, control electrode, and screen electrode, an oscillatory circuit between said anode and control electrode, said anode, screen and control electrodes being of cylindrical form, the dimensions being such that the logarithm of diameter ratio of anode and screen electrode is related to the logarithm of the diameter ratio of screen and control electrode substantially as the optimum anode alternating potential and optimum control electrode alternating voltage.

5. An oscillation generator circuit for the production of extremely high frequencies comprising an electron discharge device having an anode, cathode, control electrode, and screen electrode, an oscillatory circuit between said anode and control electrode, said anode, screen and control electrodes being located in different parallel planes, the dimensions being such that the ratio of the distance between the screen and the anode to the space intervening between the control electrode and the screen is substantially equal to the ratio between the optimum anode alternating voltage and the optimum control electrode alternating voltage.

6. An oscillation circuit comprising an electron discharge device on whose anode and grid are voltages the phases of which are in opposition whereby the alternating potential at some point between the anode and grid is zero, and a screen grid located between said anode and grid at said zero point.
